UNITED STATES PATENT OFFICE.

FRANK DE MINICO, OF NEW YORK, N. Y., ASSIGNOR TO POLLARD-ALLING MANUFACTURING COMPANY, OF NEW YORK, N. Y., A CORPORATION OF NEW YORK.

PRINTING MACHINE.

1,421,920.

Specification of Letters Patent. Patented July 4, 1922.

Application filed June 9, 1921. Serial No. 476,120.

To all whom it may concern:

Be it known that I, FRANK DE MINICO, a citizen of the United States, and a resident of New York, borough of Bronx, in the 5 county of Bronx and State of New York, have invented certain new and useful Improvements in Printing Machines, of which the following is a specification.

This invention relates to printing machines and particularly to that class thereof which is adapted for printing from small embossed plates such as shown in Fig. 7 of Letters Patent of the United States No. 866,863 of September 24, 1907 to G. F. Hopkins.

The object of my improvements is to provide a machine of the class specified, of simple construction, and which can be rapidly and easily manipulated for printing upon 20 envelopes, labels and the like.

With these ends in view and others which will appear hereinafter my improvements comprise features illustrated in their preferred embodiment in the drawings accompanying this specification, wherein:

Figure 1 is a perspective view of my improved machine. Fig. 2 is a side elevation partly in section on line 2—2 of Fig. 3. Fig. 3 is an end view in section on line 3—3 of 30 Fig. 2. Fig. 4 is a fragmentary elevation showing a detail of the machine.

While for quantity production it is customary to employ the above mentioned embossed plates assembled into a continuous 35 chain and which chain of plates is fed automatically through an elaborate machine, in many cases it is desirable and convenient to print from the plates one at a time and my present machine is for such purpose.

Table 2 may be conveniently mounted on legs, as 3, preferably having rubber feet, as 4. In the front end of said table about midway its width is depressed portion 5 forming a seat onto which an individual printing 45 plate 6 is slid, under ink ribbon 7. Said ribbon is mounted on opposite spools 8, 9, being fed from one to the other as required, by turning the receiving spool by hand. Ribbon 7 passes from spool to spool, crosswise 50 over table 2 and beneath top-plate 10, and which plate has an opening at the printing end of the machine between portions 11 and 12, directly over seat 5 for the printing plate. An envelope 13 or other article to be 55 printed is placed, face down, on top-plate

10, with the portion on which it is desired to print over the opening between portions 11 and 12. Directly below that portion of said envelope over said opening, and below plate 10 is ribbon 7, and below the ribbon 60 is printing plate 6, with its embossed characters face up. With the several parts and the envelope in the described positions it is obvious that any downward pressure brought to bear on that portion of the envelope over the opening in plate 10 will cause the embossed characters on printing plate 6 to press the ink ribbon against the under face of the envelope, thereby printing those characters on said envelope. To accomplish this result I preferably employ the following means: Upstanding from table 2 near that end remote from the printing plate seat 5 are ears 14, 15 spaced apart sufficiently to permit the free reciprocation 65 therebetween of lever 16. Said lever is slotted at 17 and is retained between said ears by pin 18 extending through said ears and through said slot. The lever is thus permitted to swing up and down on said pin 70 75 and to move a limited amount back and forth lengthwise the machine parallel with printing plate seat 5. Fixed to the rear end of said lever is weight 19, and near the forward free end of said lever impression roll 80 85 90 95 100 105 110 20 turns freely on stud 21 outstanding from said lever. Said roll is preferably of some yieldable material such as rubber and is adapted to traverse back and forth over the length of plate 6 as permitted by slot 17 of lever 16 on pin 18. On that side of lever 16 opposite roll 20 is mounted on eccentric pin 22 gage roll 23 for engagement with plate 10. This roll 23 is efficient for gaging and maintaining the distance of impression roll 20 from plate 6 as that roll 20 is moved to perform its work. Said eccentric pin 22 may be rotated to move roll 23 up or down relatively to roll 20 and may be held in any adjusted position by set screw 24. A suitable handle 25, projecting from the free end of lever 16, is used to operate said lever. The weight of that portion of lever 16 and its appurtenances to the right of pin 18, when that lever is in its forward position, Fig. 1, is greater than the weight of that portion including weight 19 to the left of said pin, but when said lever is pushed its full stroke to the left, that left hand end overbalances the right hand end.

These features contribute to the following mode of operation: In its idle position lever 16 stands as shown in dotted lines in Fig. 2, its weighted end being down, and the end 5 carrying the rolls and handle being pointed upwardly near the rear end of the machine. A printing plate 6 having been inserted on seat 5 below ribbon 7 and an envelope having been placed in position above said ribbon 10 on plate 10, handle 25 is grasped and lever 16 swung downwardly and pulled forwardly until the left hand end of slot 17 engages pin 18, Fig. 2. Then the lever is further lowered until roll 23 encounters 15 plate 10, at which time roll 20 will engage envelope 13 with the requisite amount of pressure, roll 23 having been previously adjusted to that end. The several parts will then be as shown in Fig. 1 with roll 20 at 20 the beginning of its stroke. Handle 25 is then pushed to the left, Fig. 2, and at the same time a gentle downward pressure is maintained to keep roll 23 in contact with plate 10. Roll 20 is thus caused to traverse 25 over the envelope the distance permitted by fixed pin 18 in slot 17, that is, over the length of the printing plate. The handle is then released and the end carrying weight 19 immediately drops, thereby lifting rolls 30 20, 23 from the table. The envelope is then free to be removed and another inserted. At this time another printing plate may be substituted for the one just used and from time to time the ribbon is shifted to a fresh portion 35 as needed.

I claim:

1. A printing machine including in combination means for supporting a printing plate, means for supporting an ink ribbon 40 above the printing plate support, a lever mounted for movement in the direction of its length, an impression roll pivotally mounted on said lever, and a pivot on which said lever is mounted for oscillation normal to 45 the direction of its length toward and away from said table.

2. A printing machine including in combination a table, a seat in said table for a printing plate, means for supporting an ink ribbon 50 over the printing plate seat, a lever mounted for movement in the direction of its length, means for limiting said movement, an impression roll pivotally mounted on said lever, and a pivot on which said lever is 55 mounted for oscillation normal to the direction of its length toward and away from said table.

3. A printing machine including in combination means for supporting a printing plate, means for supporting an ink ribbon 60 above the printing plate support, a lever mounted for movement in the direction of its length, an impression roll pivotally mounted on said lever, a pivot on which said lever is mounted for oscillation normal to the

direction of its length toward and away from said printing plate support, and means for gaging the distance of the impression roller from said support.

4. A printing machine including in combination means for supporting a printing plate, means for supporting an ink ribbon above the printing plate support, a lever mounted for movement in the direction of its length, an impression roll pivotally mounted on said lever, a pivot on which said lever is mounted for oscillation normal to the direction of its length toward and away from said printing plate support, means for gaging the distance of the impression roller from said support, and means for adjusting the distance of the impression roller from said support. 70 75 80

5. A printing machine including in combination means for supporting a printing plate, a lever mounted for movement in the direction of its length, an impression roll pivotally mounted on said lever, a pivot on which said lever is mounted for oscillation normal to the direction of its length toward 85 90 and away from said printing plate support, the weight of the roll-carrying end of said lever being greater than the weight of the other end thereof when said roll is in its remote position relatively to the lever pivot and said roll end being less in weight than the other end when said roll is in nearest position to said pivot, said pivot being the fulcrum. 95

6. A printing machine including in combination a table, a seat in said table for a printing plate, a lever mounted for movement in the direction of its length, means for limiting said movement, an impression roll pivotally mounted on said lever, and a pivot on 100 105 which said lever is mounted for oscillation normal to the direction of its length toward and away from said table, the weight of the roll carrying end of said lever being greater than the weight of the other end thereof when said roll is in its remote position relatively to the lever pivot and said roll end being less in weight than the other end when said roll is in nearest position to said pivot, said pivot being the fulcrum. 110 115

7. A printing machine including in combination a table, a seat in said table for a printing plate, a lever mounted for movement in the direction of its length, and an impression roll and a gage roll pivotally mounted on said lever, said impression roll being adapted for traversing a printing plate on said seat, said gage roll being adapted for simultaneously traversing the face of the table adjacent said printing plate seat and for maintaining the periphery of said impression roll at a predetermined distance from said plate seat. 120 125

8. A printing machine including in combination a table, a seat in said table for a print- 130

- ing plate, a lever mounted for movement in the direction of its length, an impression roll pivotally mounted on one side of said lever, and a gage roll pivotally mounted on the other side of said lever, said impression roll being adapted for traversing a printing plate on said seat, said gage roll being adapted for simultaneously traversing the face of the table adjacent said printing plate seat and for maintaining the periphery of said impression roll at a predetermined distance from said plate seat.
9. A printing machine including in combination a table, a seat in said table for a printing plate, a lever mounted for movement in the direction of its length, an impression roll and a gage roll pivotally mounted on said lever, said impression roll being adapted for traversing a printing plate on said seat, said gage roll being adapted for simultaneously traversing the face of the table adjacent said printing plate seat and for maintaining the periphery of said impression roll at a predetermined distance from said plate seat, and means for axially adjusting one of said rolls relatively to the other.
10. A printing machine including in combination a table, a seat in said table for a printing plate, a lever mounted for movement in the direction of its length, an impression roll pivotally mounted on one side of said lever, a gage roll pivotally mounted on the other side of said lever, said impression roll being adapted for traversing a printing plate on said seat, said gage roll being adapted for simultaneously traversing the face of the table adjacent said printing plate seat and for maintaining the periphery of said impression roll at a predetermined distance from said plate seat, and means for axially adjusting one of said rolls relatively to the other.

In witness whereof, I hereby affix my signature this 7th day of June, 1921.

FRANK DE MINICO.
